United States Patent Office.

MARK T. McCORMICK, OF MEADVILLE, PENNSYLVANIA.

Letters Patent No. 66,372, dated July 2, 1867.

IMPROVED DRILLING AND PUMPING APPARATUS.

The Schedule referred to in these Letters Patent and making part of the same.

TO ALL WHOM IT MAY CONCERN:

Be it known that I, MARK T. McCORMICK, of the city of Meadville, in the county of Crawford, and State of Pennsylvania, have invented a new and improved Machine for Sinking Artesian Wells; and I do hereby declare that the following is a full and exact description of the same, reference being had to the accompanying drawings and the letters of reference marked thereon.

The object of my invention is to drive iron pipe to the depth required to find water, and in doing this the pipe will frequently strike "hard-pan" or rock, which would prevent its being farther driven unless a hole could be drilled through the rock or "hard-pan." My machine is a combined drill and "ram" to drive the pipe after the drill, and at the same time, whenever it is desired, a pump can be attached to test the well.

Figure 1 is a front elevation of my machine.

A are the sills of the frame, on which the upright posts B C C are erected. H is a cogged driving-wheel.

Y is a smaller cogged wheel gearing into H, and may be thrown in and out of gear by any suitable device. W W is the drill-stem with a pin at x.

D is a lever, which, on the removal of a pin, 8, and the pin x, falls down in the position shown in Figure 8. The lever D is operated by the pin 5 in the small cogged wheel Y. This moves the drill-stem w w up and down, thereby giving "a blow" to the drill which is necessary in going through rock.

The drill-stem w w is square, and passes through the small "bevel-gear" wheel G, which gears into the driving-wheel H. The drill-stem is constructed so as to move freely up and down through the wheel G, and by this construction the wheel G gives the drill-stem a rotary motion, while the lever D gives it an up and down motion or "a blow."

M is a segment of cogs from 6 to 7, attached to the face of the wheel H.

O is the "driving-ram." P and P' are two guide-rods; the one, P', having a cogged rack, N, at its upper end. This rack gears into the segment M as the wheel H revolves, thereby lifting the ram O the length of the rack N once at every revolution of the wheel H, and when the segment M has passed letting the ram drop on the head of the pipe Z Z.

Fig. 1 shows the ram up, and Fig. 8 the ram down on the head of the pipe Z Z.

Z Z is the well-tube, which is constructed in sections, and screws together in the couplings a a.

The lower end of the drill-stem w w screws into a short piece of tube of the size of the inside of the well-tube Z Z. This short piece of tube is perforated with holes, as shown at S, and the drill-head R is screwed on the lower end of the same, and when the well is sunk to the desired depth, the well-tube Z Z is drawn up, or the hole is drilled down a few inches lower than the tube Z Z, and the water enters through the holes in S into the well-tube; S acting as a strainer to prevent the entrance of gravel. In sinking a well through soil, if there is no rock in the way, it is not necessary that the drill should have a "blow" or an up and down motion, but only a rotary motion, and for this purpose the lever D is detached by the removal of the pin x, and then lifting the lever D in the position shown in fig. 1, and inserting the pin 8. The drill will now have a rotary motion only, and at every revolution of the wheel H the ram will make one blow on the tube Z Z, thus driving the tube down after the drill R. Now when the drill R strikes a rock so hard that the drill cannot cut through it, and it is found necessary to use another drill, like m, Figure 4, the tube Z Z must be drawn and the drill R removed, and a drill, m, fig. 4, put in its place. This drill is constructed as follows, to wit: 3 is a steel point, with a "chisel"-shaped cutting face at 3; 1 and 2 are wings of steel, welded on the point at 4, with cutting edges at 1, 2. The tube Z Z, and drill-stem, with drill m, fig. 4, are now inserted in the well-hole; the lever D lowered on and attached to the drill-stem w w; the wheel Y thrown in gear, and as the pipe or well-tube cannot be driven while we are using this drill, the ram is lifted to the position shown in Figure 5, and there held by a catch. This position lifts the cogged rack N above the reach of the segment M. Thus the ram remains stationary while the drill has the two motions before described, i. e., up and down, and rotary.

Figure 2 is a side view of my machine, with the tube Z Z hidden by the post C. d is a balance-wheel, and n a band-pulley. The balance of drawing heretofore described in front view.

Figure 6 represents a front view of my invention with pump attachment.
